Primary Examiner — Lauren D Mcvey*Assistant Examiner* — Sarah L Smith(74) *Attorney, Agent, or Firm* — Tarter Krinsky & Drogin LLP(57) **CLAIM**

The ornamental design for an arm launched projectile toy, as shown and described.

DESCRIPTION

FIG. 1 is a side perspective view of the arm launched projectile toy showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another side perspective view of the article shown in use.

The broken lines shown in the drawings depict environment and portions of the article which form no part of the claimed design.

1 Claim, 8 Drawing Sheets(56)
